ELECTRIC ARC AND METHOD OF
PRODUCING SAME

Clarence S. Ashcraft, Los Angeles, Calif.

Application April 16, 1934, Serial No. 720,762

12 Claims. (Cl. 176—52)

My invention relates to an electric arc and a method of producing same and is of utility in motion-picture projectors, search-lights, etc.

In the art to which this invention appertains, it is common practice to provide an arc or flame by sending an electric current of suitable voltage through a pair of carbons which are disposed with their ends adjacent to each other, thus producing a flame or flames between the ends of these carbons.

There are in general use at the present time two types of electric arcs, one the so-called low intensity arc and the other the so-called high intensity arc such as is disclosed in the patent to

Sperry for Method of operating flaming arc lights for projectors, No. 1,227,210, issued May 22, 1917.

The low intensity arcs have great economy and low maintenance costs but the light produced thereby is of a yellowish color and is therefore not well suited for use in motion-picture projectors, in which art my invention is of particular utility.

The so-called high intensity arc produces good screen illumination but has certain disadvantages. In the first place, the maintenance costs are very high. Due to high amperage and voltage the carbons burn very rapidly, and, furthermore, there is a relatively high cost in the replacement of parts which quickly deteriorate due

to the high intensity operating conditions of such arc. Furthermore, the operating costs are relatively high by reason of a high power consumption. Although this so-called high intensity arc produces good illumination, the light is of a bluish white color which is better adapted for motion-picture projection work than the yellowish colored light produced by the so-called low intensity arc, it is not, however, the most satisfactory light.

It is an object of my present invention to provide a method of producing and operating a so-called high intensity electric arc in which excellent illumination or light intensity is attained, in which there is great economy by reason of low

carbon consumption, in which the maintenance costs are low because the replacement of parts is less frequent, in which the operating costs are low due to a relatively low power consumption, and in which the light produced thereby is of a pure white color.

It is an object of my invention to provide a method of producing or operating an electric arc which will produce a white uniform shaft of light which is particularly suited for motion-picture projection work.

Another object of the invention is to provide a method of producing an electric arc in which a positive flame of luminescent gas is substantially flattened adjacent the positive crater such

that the flattened portion substantially completely covers the area of crater.

Another object of the invention is to provide a method of producing an electric arc in which the luminescent gas of the positive flame is in contact with substantially the entire area of the crater.

Another object of the invention is to provide a method of producing an electric arc in which a positive flame of luminescent gas is mushroomed by a negative flame.

Another object of my invention is to provide a method of producing or operating an electric arc which will produce an arc or flame which has a substantially symmetric or concentric luminescent area.

It is another object of my invention to provide a method of producing an electric arc in which luminescent gas of the positive flame of the arc is caused to flow evenly from the crater of the positive electrode and is then flattened to provide a symmetric or concentric luminescent area.

Another object of my invention is to provide a method of producing an electric arc in which a negative flame is directed against a positive flame to produce a body of luminescent gas having a substantially flattened surface and having its periphery extending rearwardly and surrounding the end of the positive electrode.

It is a further object of my invention to provide a method of operating an electric arc in which the crater of the positive electrode is of substantially isothermperature.

A still further object of my invention is to provide a method of producing an electric arc in which the crater of the positive electrode burns evenly and therefore requires no rotation.

It is a still further object of my invention to provide a method of operating an electric arc in which the electrodes are in axial alignment, in which the positive and negative flames oppose each other.

Other objects and advantages of my invention will be pointed out in the following description.

For the purpose of explaining my invention to those skilled in the art in order that they may practice the same, I will describe in detail a method of the preferred form of my invention. In the description which follows I will describe the details of construction of the carbons employed, the dimensions of the parts, spacings, the current flow, and voltage, as well as other definite qualities and quantities which are involved in the performance of the preferred form in the preferred process of my invention.

It should be strictly understood that by choosing a single specific embodiment of my invention for illustrative purposes, I do not intend to be limited to the details thereof, but on the contrary intend that my invention shall be broadly

115

120

construed in accordance with the preceding statement of invention of this application and the appended claims, to cover any and every process which comes within the broad scope of my invention and utilizes the principles thereof.

For the purpose of assisting in the explanation, reference will be made to the appended drawing in which there is shown the carbons which are employed in practicing the preferred embodiment 10 of my invention and the electric arc which is produced by the preferred method of my invention. I shall now refer to the drawing in detail and describe the preferred method of my invention.

The numeral 11 is a positive electrode, and the 15 numeral 12 is a negative electrode, both of which are carbon and preferably copper coated as at 14. The positive electrode has a core 15 composed of a material which during operation produces a brilliant gaseous positive flame. The negative electrode has a core 16 of arc-sustaining material. The positive electrode is 7 mm. in diameter, and the negative electrode is 6 mm. in diameter. The two electrodes are in axial alignment 20 on the axis A—A. During operation the positive electrode is formed with a crater 17 which is about .245" in diameter, and the negative electrode is formed with a rounded end 18. The distance between the ends of the electrodes, as indicated at B, is $\frac{1}{4}$ " and is maintained approximately 25 thereat during operation by manually or automatically operated means.

This is the construction of the positive and negative electrodes which I prefer to use in practicing my invention. Obviously, as aforesaid, my invention is not limited to this particular apparatus.

In practicing my invention, the electrodes are connected in a direct current electric circuit capable of providing the required current and voltage. To start the arc, the electrodes are moved 40 into contact and are then returned to the desired spaced position.

The negative flame 20 which is of relatively even density issues from the rounded end 18 of the negative electrode 12 substantially concentric to the axis A—A and diverges toward the positive electrode 11, and has a substantially frusto-conical shape. In this embodiment the angle between the sides of the negative flame 20 is substantially 45 69° , which due to the upward draft produced by heat is substantially 36° above and 33° below the axis A—A.

If there is no crater 17 in the end of the positive electrode when starting the method, the core 50 15 will burn away and form a crater.

The positive flame 21 is formed in the crater 17. It consists essentially of the gas formed by the burning of the core 15 and is highly luminescent. This flame issues from the crater and toward the negative electrode. The two flames meet at line 60 23 and the positive flame is flattened into a disc which is substantially concentric to the axis A—A and is approximately $\frac{37}{32}$ " in diameter. The peripheral portion, when conditions are most desirable, is forced rearwardly as at 24 so as to surround the end of the positive carbon, and is useful in adding heat to the end of the positive carbon so as to produce an isothermal condition in the walls forming the crater. This is of assistance in producing an evenly distributed issuance 70 of luminescent gas from the crater.

In practicing my invention, I find that the current density must be high enough to produce the luminescent gas in a volume which will issue from the crater and at the same time must be

below the point where the pressure of the negative flame against the positive flame will tend to break through or destroy the luminescent disc. For example, in practicing my invention with the sizes and construction illustrated in the accompanying drawing, the luminescent gas does not form in desired quantities until the current flow is approximately 40 amperes. As the current flow is increased, the volume of luminescent gas which is produced is increased; and also the pressure of the negative flame is increased. During this increase the negative flame pressure appears to gradually build up to the point where the positive flame is flattened into a disc. It appears from observation that the positive flame at this point is not forced back around the positive electrode as at 24; however, the luminescent area is present in the form of the concentric disc and produces favorable results, and the invention may be so practiced. Upon further increasing the current 80 amperage, I am able to force the peripheral portion 24 of the positive flame rearwardly to surround the end of the positive electrode and in this way use the heat thereof to assist in evenly heating the walls of the crater 17. If the current flow is increased too much, the forming of the luminescent disc is impaired. The luminescent gas does not issue evenly from the crater 17 and the negative flame tends to break through the positive flame, and the results obtained are inferior to those obtained at lower current flows. With the apparatus disclosed I have operated with a current as low as 40 amperes and as high as 65 amperes; but the best results, such as is illustrated in the accompanying drawing, were 90 obtained with a current of 46 amperes and a gap 100 voltage of 36 volts.

By the term "luminescent gas" as used in the claims is meant any gas giving a brilliant flame and includes a gas in which incandescent particles 110 may be present.

I claim as my invention:

1. The method of producing an electric arc in an arc lamp which comprises forming luminescent gas in a crater of a positive electrode in such 120 volume that it issues outwardly therefrom, and directing a flame from a negative electrode against said luminescent gas so as to produce a body of luminescent gas having a substantially flattened surface, the periphery of said body extending rearwardly to form a portion completely surrounding the end of said positive electrode.

2. The method of producing an electric arc in an arc lamp which comprises forming luminescent gas in a crater of a positive electrode in such 130 volume that it issues outwardly therefrom, and directing a flame from a negative electrode against said luminescent gas so as to produce a body of luminescent gas having a substantially flattened surface, the periphery of said body extending rearwardly to form a portion completely 135 surrounding the end of said positive electrode and substantially concentric therewith.

3. A method of producing an electric arc which comprises placing a positive electrode, having a 140 core capable of forming a flame of luminescent gas in said arc, adjacent a negative electrode, forming a crater in said positive electrode, directing a flow of luminescent gas outwardly therefrom and toward said negative electrode, and directing a negative flame against said luminescent gas to form a flame having a substantially flattened surface opposite said negative electrode and to cause said luminescent gas to flow outwardly and 145 150

- rearwardly so as to form a portion completely surrounding the end of said positive electrode.
4. The method of producing an electric arc which comprises positioning a positive electrode, capable of emitting a positive flame of luminescent gas, adjacent a negative electrode, causing a current to flow between said electrodes sufficient to form said luminescent flame and a negative flame, directing said negative flame 80 against said positive flame in such a manner as to form a crater in said positive electrode and substantially flatten a portion of said luminescent flame so as to form a substantially flattened luminescent surface in front of the crater, whereby the crater is substantially completely covered by said flattened portion of said luminescent flame and said luminescent gas contacts substantially the entire area of said crater.
5. The method of producing an electric arc which comprises positioning a positive electrode, capable of emitting a positive flame of luminescent gas, adjacent a negative electrode, causing a current to flow between said electrodes sufficient to form said luminescent flame and a negative flame, directing said negative flame against 95 said positive flame in such a manner as to form a crater in said positive electrode and substantially flatten the surface of at least a portion of said luminescent flame so that the area of said flattened surface exceeds the area of the crater projected axially of the positive electrode upon said flattened surface, whereby the crater is substantially completely covered by said flattened portion of said luminescent flame and said luminescent gas contacts substantially the entire area of said crater.
6. The method of producing an electric arc which comprises positioning a positive electrode, capable of emitting a positive flame of luminescent gas, adjacent a negative electrode and substantially coaxial therewith, causing a current to flow between said electrodes sufficient to form said luminescent flame and a negative flame, directing said negative flame against said positive flame in such a manner as to form a crater in 110 said positive electrode and substantially flatten a portion of said luminescent flame so as to form a substantially flattened luminescent surface in front of the crater, whereby the area of the crater is substantially completely covered by said flattened portion of said luminescent flame and said luminescent gas contacts substantially the entire area of said crater.
7. The method of producing an electric arc which comprises maintaining an arc across a gap of approximately $\frac{1}{4}$ of an inch between a positive electrode, capable of forming a positive flame of luminescent gas, and a negative electrode, causing sufficient current to flow to form 120 said luminescent flame and a negative flame, directing said negative flame against said positive flame in such a manner as to form a crater in said positive electrode and substantially flatten a portion of said luminescent flame so as to form a substantially flattened luminescent surface in front of the crater, whereby the area of the crater is substantially completely covered by said flattened portion of said luminescent flame and said luminescent gas contacts substantially the entire area of said crater.
8. The method of producing an electric arc which comprises positioning a positive electrode, capable of emitting a positive flame of luminescent gas, adjacent a negative electrode, causing 130 a current to flow between said electrodes sufficient to form said luminescent flame and a negative flame, directing said negative flame against said positive flame so as to cause the positive flame to be mushroomed.
9. The method of producing an electric arc which comprises positioning a positive electrode, capable of emitting a positive flame of luminescent gas, adjacent a negative electrode, causing a current of approximately 40 to 65 amperes to flow between said electrodes in order to form said luminescent flame and a negative flame, directing said negative flame against said positive flame in such a manner as to form a crater 135 in said positive electrode and substantially flatten a portion of said luminescent flame so as to form a substantially flattened luminescent surface in front of the crater, whereby the area of the crater is substantially completely covered by said flattened portion of said luminescent flame and said luminescent gas contacts substantially the entire area of said crater.
10. The method of producing an electric arc which comprises positioning a positive electrode, capable of emitting a positive flame of luminescent gas, adjacent a negative electrode, forming a crater in said positive electrode, forming said flame of luminescent gas in contact with substantially the entire area of said crater, substantially flattening at least a portion of said flame adjacent said crater, and maintaining said flattened portion in a position to substantially completely cover the entire area of said crater.
11. The method of producing an electric arc which comprises positioning a positive electrode, capable of emitting a positive flame of luminescent gas, adjacent a negative electrode, causing a current to flow between said electrodes sufficient to form said luminescent flame and a negative flame, balancing the pressure of the negative flame against the pressure of the positive flame so as to form a crater in said positive electrode with said luminescent flame in contact with substantially the entire area of the 140 crater and so as to substantially flatten the surface of said luminescent flame and maintain said flattened surface in front of said crater so that the projection of said crater area axially of said positive electrode falls substantially completely within the margins of said flattened surface.
12. The method of producing an electric arc which comprises positioning a positive electrode, capable of emitting a positive flame of luminescent gas, adjacent a negative electrode, causing a current to flow between said electrodes sufficient to form said luminescent flame and a negative flame, and directing said negative flame against said positive flame so as to cause the positive flame to be mushroomed.

CLARENCE S. ASHCRAFT.
